John L. Tedaldi, Maplewood, and Jerome A. Gross, Clayton, Mo., assignors to Design Stamping Corporation, St. Louis, Mo., a corporation of Missouri

Application February 24, 1953, Serial No. 23,735

Term of patent 14 years

(Cl. D80—11)

To all whom it may concern:

Be it known that we, John L. Tedaldi and Jerome A. Gross, citizens of the United States and residents, respectively, of the city of Maplewood, county of St. Louis, State of Missouri, and the city of Clayton, county of St. Louis, State of Missouri, have jointly invented a new, original, and ornamental Design for a Display Case Corner, of which the following is a specification, reference being made to the accompanying drawing, forming a part thereof, in which

Figure 1 is a perspective view of a display case corner, embodying our new design as seen from the outside above said corner and to the left thereof; and

We claim:

The ornamental design for a display case corner, as shown.
